UNITED STATES PATENT OFFICE.

CHARLES H. ECKERSON, OF CLOSTER, NEW JERSEY, ASSIGNOR OF ONE-HALF TO GORDON J. SCOTT, OF ENGLEWOOD, NEW JERSEY.

CAMERA.

1,226,955.

Specification of Letters Patent.

Patented May 22, 1917.

Application filed April 5, 1916. Serial No. 32,992.

To all whom it may concern:

Be it known that I, CHARLES H. ECKERSON, a citizen of the United States, residing at Closter, in the county of Bergen and State of New Jersey, have invented certain new and useful Improvements in Cameras, of which the following is a full, clear, and exact description.

In using photographic cameras, particularly of the type using "roll-film," need has been felt for means whereby each exposed portion of the film can be marked, at the time of making the exposure, with such data as may be desirable, as for example the title of the picture, the date, the duration of the exposure, the stop used, etc. Various schemes, more or less successful, have been devised for the purpose.

My present invention relates to this idea, and its chief object is to provide simple and reliable means whereby successful results in use will be secured with certainty. A further object is to provide for the purpose means that can be applied to existing types of cameras at slight expense. To these and other ends the invention consists in the novel features and combinations hereinafter described.

One form of the invention is illustrated in the accompanying drawing, in which—

Figure 1 shows in plan the back of a roll film camera, equipped with my invention.

Figs. 2 and 3 are enlarged detail sectional views on lines 2—2 and 3—3 respectively of Fig. 1.

Fig. 4 is an inside view of a part of the camera-back.

In carrying out the invention in the preferred manner the camera-back 10, which is usually removable at will from the camera-body, not shown, is formed at one end, just beyond the area in which the film is exposed, with a transverse exposure opening 12, provided with a movable frame 12^a supported by means of spring tongues 12^b and fixed in the bottom of this frame is a piece 13 of translucent material, the thinner the better, the outer surface of which has a slight "tooth" so it can be written on with an ordinary lead pencil. The best material I know of for the purpose is thin sheet celluloid, finely ground or frosted on one side. This material is unbreakable and hence preferable to glass. The writing can be wiped off

the celluloid with the moistened finger, a method of erasure that is not, in general, practicable with paper.

Under the celluloid strip 13 is a thin shutter 14, preferably as stiff as possible. For that reason, and for the sake of durability, I prefer to make the shutter of thin sheet steel. The shutter is slightly larger than the opening 12, and normally covers the celluloid, as shown in Figs. 1 and 2, so that no light can penetrate to the film. On one edge it is provided with a tongue 15 to which is fixed a button 16 working in a longitudinal slot 17 in the camera-back.

The backing paper 18 of the film 19 is slightly translucent, or at least it has translucent areas spaced at such distances apart as to come into register with the opening 12 when successive portions of the film are drawn off the spool for exposure through the lens. It will be understood that although a single layer of the paper permits some light to pass, the several wrappings or turns of the paper around the roll before and after it is used will be usually sufficient to protect the film from light. If desired the paper may have its end portions opaque.

The method of using the invention will now be readily understood.

When it is desired to mark the film, the user writes the desired data on the celluloid strip 13 with a lead pencil, preferably soft and rather blunt so as to give a heavy, black line. He then slides back the shutter 14 by applying the finger or thumb to the button 16, and exposes the opening to strong light, as for example to the direct light of the sky. The light passing through the frosted celluloid and the translucent paper, "exposes" the film except where the pencil marks on the celluloid prevent the light from passing. The result is that when the film is developed and fixed the writing will be transparent or substantially transparent, on a black surface. It will also be observed that although the user writes on the celluloid from left to right in the usual way, the writing on the film is reversed, and comes "right" again on prints made from the negative. The exposure having been made as just described, the shutter is closed and the film wound for the next picture. When the shutter is drawn back, the spring tongues 12^b press the celluloid strip down

upon the backing paper 18 so as to have the writing as close to the film as possible during exposure.

If desired, a pair of springs 20 may be provided, mounted on the inside of the camera back at each side, to bear on the edges of the film and hold the latter in the focal plane. Grooved guide rails 21 may be provided on the camera-back, for example at each end of the shutter, to guide the latter and prevent binding, thereby insuring smooth working, and to support the shutter when the user is writing on the celluloid strip.

15 The celluloid strip 13 is preferably removable, being held in place by inwardly projecting flanges 22 on three sides of the opening 12, shown in Fig. 4. When it becomes necessary or desirable to renew the 20 celluloid, the old strip can be drawn out and a fresh one inserted in the manner illustrated in Fig. 4.

In the camera-back is the usual window 23, glazed with transparent red or orange 25 material, through which the numbers on the film-backing-paper are displayed. If this paper is translucent where the numbers are printed the film may be fogged at such points by the prolonged action of light 30 through the opening, even though the transparent material in the opening, is red. To avoid the possibility of fogging, the opening can be provided with an opaque closure 24 which can be slid back momentarily by 35 means of a button 25 whenever the operator desires to look at the film number.

It is to be understood that the invention is not limited to the particular form herein specifically illustrated and described, but can be embodied in other forms without departure from its spirit.

I claim:

1. A camera having an opening in position to permit light to strike through the same to a suitable portion of the film, an inwardly and outwardly movable piece of celluloid arranged in said opening and having its outer surface ground or frosted, a sliding opaque shutter of stiff material arranged underneath the celluloid and normally holding the same in its outer position, and spring means carrying the celluloid and urging the same inwardly, whereby to press the celluloid into close proximity to the film when the shutter is withdrawn.

2. A camera-back having an opening at one end of the exposure area, a frame fitting said opening but movable inwardly and outwardly therein, spring means normally urging the frame inwardly, a piece of sheet 60 celluloid mounted in the bottom of the frame and having its outer surface ground or frosted, and a sliding opaque shutter movable under the frame, adapted to support the frame in its outer position during the act of writing on the celluloid and permit inward movement of the frame under the influence of said spring means when the shutter is slid from under the frame.

In testimony whereof I hereunto affix my signature.

CHARLES H. ECKERSON.
